US0D1073695S

(12) **United States Design Patent** (10) **Patent No.:** **US D1,073,695 S**
(45) **Date of Patent:** ** *May 6, 2025

(54) **DISPLAY SCREEN OR PORTION THEREOF WITH GRAPHICAL USER INTERFACE**

(71) Applicant: **AGCO Corporation**, Duluth, GA (US)

(72) Inventor: **Lucas Andrew Weller**, Hesston, KS (US)

(73) Assignee: **AGCO Corporation**, Duluth, GA (US)

(*) Notice: This patent is subject to a terminal disclaimer.

(**) Term: **15 Years**

(21) Appl. No.: **29/880,551**

(22) Filed: **Jul. 25, 2023**

(51) LOC (15) Cl. **14-04**

(52) U.S. Cl.

USPC **D14/485**

(58) **Field of Classification Search**

USPC D14/485-495

(57) **CLAIM**

The ornamental design for a display screen or portion thereof with graphical user interface, as shown and described.

DESCRIPTION

FIG. 1 is a front view of a display screen or portion thereof with graphical user interface, showing the new design; FIG. 2 is a front view of another embodiment thereof; FIG. 3 is a front view another embodiment thereof; and, FIG. 4 is a front view another embodiment thereof.

The outermost broken-line rectangle in each of the figures shows the display screen or a portion thereof and forms no part of the claimed design.

1 Claim, 2 Drawing Sheets
